Specification of Letters Patent.

Patented July 28, 1914.

Application filed June 21, 1909, Serial No. 503,345. Renewed September 14, 1912. Serial No. 720,420.

To all whom it may concern:

Be it known that I, ELMER R. CORWIN, a citizen of the United States, residing at Chicago, in the county of Cook and State of Illinois, have invented a certain new and useful Improvement in Telephone Systems, of which the following is a full, clear, concise, and exact description, reference being had to the accompanying drawings, forming a part of this specification.

My invention relates to telephone exchange systems, and has for one of its objects the provision of a telephone exchange system whereby calling lines are automatically connected with responsive apparatus belonging to operators that are not busy, or, in other words, that are at liberty to attend to the wants of the calling subscribers.

My invention, in its usual or most common embodiment, may generally be described as being a telephone exchange system including lines extending from telephone stations to an exchange, a plurality of groups of operators' link connectors at the exchange, responsive devices for said group of link connectors, and selecting mechanism governed by calling lines adapted to select responsive devices free for selection; said link connectors being adapted to their telephone line joining function independently of the aforesaid selecting mechanism. In the preferred embodiment of the invention the responsive devices control the association of conductors leading to the operators' telephones and there is preferably but one responsive device to each group of link connectors, though I do not wish to be limited to this characteristic. I have also provided operator controlled means for freeing the responsive devices so that they may be subject to further selection.

I use the term "groups of link connectors" in the sense of sets of link connectors and with no regard to any segregation of the link connectors into physically distinct collections.

My invention would be useful in a very small exchange since by means of it signals individual to the lines leading to the exchange are not required. A preferred form of telephone exchange system accomplishing this feature of my invention may generally be described as including lines extending

from telephone stations to an exchange, a plurality of groups of operators' link connectors at the exchange for uniting lines in conversation, a responsive device for each group of link connectors and desirably common to the link connectors of such group, mechanism governed by calling lines for operating the responsive devices associated with the groups of link connectors, and means for rendering such responsive devices incapable of response when the operator in charge of the group of link connectors is not at liberty to attend to the wants of calling subscribers. The means that are employed for thus rendering the responsive devices unresponsive are furnished to the operator, to be used independently of the link connectors and are furnished to the operator to be used in connection with the link connectors, so that while the operator is making a connection or is about to make a connection, she will not be interrupted. I preferably also employ means for rendering the responsive devices unresponsive, that are governed by the mechanism that has selected a responsive device, so that other selecting mechanism will pass by the selected responsive device until it finds a responsive device that is free for selection.

My invention also has for its object the provision of a signaling system including a plurality of signaling lines, such as telephone lines, signal receivers, selector switches for selecting signal receivers that are free for selection and associating the same with signaling lines, and means individual to the lines and which differ from each other for causing said signal receivers to give characteristic signals peculiar to the lines. In the preferred embodiment of the invention the means which are individual to the lines are in the form of phonographs capable of speaking the numbers of the lines to which they are individual, in which event the signal receivers are in the form of operators' head telephones to announce to the operator the numbers of the lines.

I will explain my invention, in its various aspects, more fully by reference to the accompanying drawings, showing one embodiment thereof, in which—

Figure 1 is a general diagrammatic view illustrating a system constructed in accord-

ance with my invention. Figs. 2 and 3 represent cord circuits of two groups located at different operators' positions.

Like parts are indicated by similar characters of reference throughout the different figures.

In Fig. 1 I have shown telephone lines that may be of any well known and suitable type, the telephone lines illustrated happening to include switch-hooks 1, telephone receivers 2, transmitters 3, signal receivers 4 and condensers 5, two stations, 120 and 190, being illustrated with this apparatus. The telephone lines, in the embodiment of the invention illustrated, each terminate at the exchange in multiple jacks 6. I have illustrated in the drawings, link connectors, each including, in the embodiment of the invention illustrated, an answering plug 7 and a connecting plug 8', these plugs having tip, sleeve, and thimble or heel contact parts united by corresponding strands. I do not wish to be limited, however, in all embodiments of my invention to link connectors employing answering plugs as well as connecting plugs nor to the use of connecting plugs. The circuits of the link connectors are immaterial to the preferred embodiment of my invention. They may be of any well known or suitable type, and I will describe none of the apparatus peculiar to the link connectors, excepting to state that each of the link connectors shown is adapted, when connected at its ends with calling and called lines, to unite such lines in conversation. For like reasons, I have omitted the illustration of parts commonly found in association with link connectors, such, for example, as supervisory signals and signaling current generating apparatus.

In Fig. 1 of the drawings, I have illustrated, at A, but one link connector of a group belonging to one operator's position and, at B, I have illustrated one link connector of a group belonging to another operator's position.

In Fig. 2, I have shown, at A, a link connector of a group belonging to one operator's position and, at B, I have shown a link connector of a group belonging to another operator's position. At each operator's position, I have shown a responsive device 8 common to the group of link connectors at such operator's position, this responsive device preferably constituting a signal-actuating device, the responsive device at position A governing the circuit of a small lamp 9, while the responsive device at station B governs the position of a mechanical display element 10.

I interpose apparatus between the responsive devices and the telephone lines whereby a calling telephone line may operate a responsive device that is free for operation, instrumentalities being employed to prevent

the responsive devices from operating when the operator at the position having such responsive devices is not free to perform work. In the embodiment of the invention illustrated, I employ selecting mechanism individual to the telephone lines and set into operation by a calling line for the purpose of operating a responsive device, such as an operator's head telephone or a signal device in response to whose signal the operator may, in any preferred way, be brought into telephonic connection with the calling subscriber, either automatically or by a listening key, the responsive device being free for operation, thereby calling the attention of the operator having such responsive device, so that such operator may effect connection between the calling and called lines.

I will first give a description of the selecting mechanism associated with each line, and will thereafter describe its inter-relation with the line and with the responsive devices.

The selecting mechanism illustrated includes a ratchet wheel 11, upon whose shaft 90 a single group of wipers 12 12¹ 12² are carried, these wipers 12 12¹ 12² being adapted to contact with waiting contacts 13 13¹ 13² associated with the responsive devices 8. Each responsive device has a plurality of groups of waiting contacts, each group containing three contacts 13 13¹ 13². Similarly related waiting contacts associated with a given responsive device are in multiple connection. The groups of waiting contacts belonging to each responsive device are distributed among the selecting devices, so that the wipers of the selecting devices in their travel will engage one group of waiting contacts belonging to one responsive device or another 100 group of waiting contacts belonging to another responsive device, or another group of waiting contacts belonging to still another responsive device, and so on. A magnet 14 is provided with an armature 15 pivoted at 110 16, said armature, when attracted, causing the actuating pawl 17 carried thereby to rotate the ratchet wheel 11 one tooth, the pawl escaping the tooth when the armature is restored, as will be seen by the illustration. 115 The winding of the magnet 14 is included in circuit with an interrupter 18 common to the selectors, and a source of current 19, which may be the grounded common battery of the exchange. The magnets 14 are individual to 120 the telephone lines, and in addition to their circuits including the interrupter 18 that is common to all of the magnets 14, said circuits also include the lowermost normal contact 20 of the locking relay 21, the lowermost normal contact 22 of the cut-off relay 23, one side of the calling subscriber's line, the calling subscriber's transmitter 3, receiver 2, switch-hook 1, the remaining side of the calling subscriber's line, to the grounded im- 130

pedance 24. During a part of the time that the selecting mechanism is in association with a selected responsive device, the locking relay 21 and the cut-off relay 23 remain inert.

It will thus be seen that as soon as a calling subscriber has removed his receiver from its switch-hook, the selecting mechanism individual to the calling subscriber's line is set into operation, and immediately after the selecting mechanism has been set into operation a circuit including the battery 19, is closed at the contacts 25, which are brought together as a consequence of the initial operation of the selecting mechanism, whereby battery 19 is connected with the test thimbles 26 of the jacks belonging to the calling line, so that no operator, excepting the one that is to be selected, will connect with a calling line. The wipers of the selecting devices are desirably normally out of contact with the contacts 13 13¹ 13² and pass over these contacts in the process of selecting a responsive device 8 that is free to be operated. Thus responsive devices are free for selection when the circuits governing the responsive devices are in their normal or idle conditions. Each responsive device has a governing circuit that may be traced from the ground 27, the manually controlled switch 28 (designed for operation by the operator to render responsive devices unresponsive), the armature switch of magnet 29, the armature switch 30 of the responsive device 8, the engaged waiting contact 13, a wiper 12 resting in engagement therewith, the follow-up contact 31, the armature switch spring engaging the same, the locking relay 21, to the grounded battery 19. The ground 27 is present as a part of such controlling circuit when the responsive device associated therewith is to be actuated, but when the responsive device is not to be selected, this ground 27 is to be removed, which removal may be accomplished in several ways, as will appear. Assuming the ground 27 to be present in the circuit controlling the associate responsive device 8, the selecting mechanism of the calling subscriber will cease operation as soon as its wiper 12 engages the waiting contact 13 connected with such ground 27, to maintain said wiper and contact in engagement and also to maintain the wipers 12¹ 12² in engagement with the waiting contacts 13¹ 13² of the selected group of waiting contacts, in order that circuit changes may be effected which remove the ground 27 from a selected responsive device and will prevent the further operation of the selecting mechanism, and also preferably to enable the operator to have telephonic connection with a calling subscriber independently of the link connecting apparatus. As a consequence of the circuit closed by way of the elements 12 13,

the armature switch spring engaging the normal contact 31 is moved to engage its grounded alternate contact, whereby circuit through the locking relay 21 is continued closed and the circuit for the magnet 14 is opened at 20 to prevent further operation of the selecting mechanism during the association thereof with the selected responsive device. As a result of the energization of the locking relay 21, the wiper 12² is connected with one side of the calling line and the wiper 12¹ is connected with the other side of the calling line, and inasmuch as the contacts 13¹ 13² engaged by the wipers 12¹ 12² are preferably connected with the operator's telephone equipment 32 or conductors leading thereto, such operator's telephone equipment or the set of conductors leading thereto is selectively brought into circuit relation with the calling line preferably independently of the link connecting apparatus 7 8'.

The operator's telephone thus constitutes a responsive device common to its group of link connectors and which is not necessarily operated as a consequence of its selection but is permitted to be operated by the calling party when speaking into his transmitter.

In order to prevent another selecting mechanism belonging to another calling line from picking out a selected responsive device, in the form of an operator's telephone or relay 8 that has become associated with a calling line, line 120, for example, the ground 27 is removed, the circuit that effects the removal of the ground 27 being traceable from the grounded battery 19 to the responsive device 8, the waiting contact 13¹, the engaging wiper 12¹, the alternate contact 33, the normal contact 22, one side of the subscriber's line, through the subscriber's station, the other side of the subscriber's line, to the grounded impedance device 24. The magnet of the responsive device 8 is thus energized to cause its armature switch 30 to leave its contact, and thereby separate the ground 27 from the normal contacts 13, whereby the wiper 12 of any other selecting mechanism will pass by said waiting contacts 13, inasmuch as no circuit is establishable for the locking relay 21 of the calling line belonging to the other selecting mechanism. In order that the operator may have control over the responsive devices 8, to determine whether or not they are to be selected, she is not only provided with the manually operated switch 28 for her responsive device, but her link connectors are also provided with mechanism that governs the association of the ground 27 with the waiting contacts 13.

In the preferred embodiment of the invention, each end of the link circuit has an electro-magnet 34¹, 34², the armature switch of each of which having a single normal contact and two alternate contacts, the up-

per one of which enters into the preferred embodiment of my invention. Each magnet 34³ has a local circuit which is established when the plug associated therewith is inserted in a jack, the circuit for each electromagnet 34³ then being traceable from the grounded battery 19 through the winding of magnet 34³, the heel contact 34¹ of the associate plug, the thimble of the jack receiving such plug, to the grounded cut-off relay 23. The normal contacts of both magnets 34³ of a link connector or cord circuit normally coöperate to establish a dead circuit. When one of the plugs only is in engagement with a jack, this dead circuit is broken and a live circuit for the magnet 29 is established, which may be traced from the grounded terminal of the magnet 29, through the listening key-operating magnet 35, the normal contact of the inert mate to the operated magnet 34³, the upper alternate contact of the energized electro-magnet 34³, to the grounded battery 19, whereby the magnet 29 is energized, its armature switch 25 is attracted, and the ground 27 is removed from the waiting contacts 13, so that a selecting mechanism of a calling subscriber is bound to pass by the waiting contacts 13 associated with the responsive device 8 from whose governing circuit the ground 27 has thus been removed. Thus the operator, in using one plug of a link connector employing two plugs, will prevent the selection of the responsive device common to the group 35 of link connectors that includes such link connector which has been taken for use. As soon as the operator has inserted the connecting plug of the link circuit taken for use, the right hand relay 34³ is energized, thereby breaking the circuit for the magnets 29 and 35 causing the operator's telephone to be disconnected from the employed link circuit and causing a restoration of the ground 27 to the circuit that governs the 45 associated responsive device 8, so that so far as the link connector-controlled magnet 29 is concerned, the responsive device 8 associated therewith is adapted again to be selected by another calling line. Taps lead from the waiting contacts 13¹, 13² at elements 35, 35¹ to similar elements of other cord circuits to make the responsive device 8 common to a plurality of groups of link connectors as well as to a plurality of selectors, there being preferably but one responsive device to an operator's position, though I do not wish to be limited to this characteristic. When the answering end of a link connector circuit has been connected with a calling line, the wipers of the selecting mechanism of such calling line are desirably shifted out of engagement with the waiting contacts, releasing the responsive device so far as the selecting mechanism is concerned. 60 To this end, I employ a releasing electro-

magnet 36, a circuit for which is established when the connecting end of the link circuit selected by the operator has been connected with the calling line, and which circuit may be traced from the grounded battery 19 through the operated switch 25, the releasing magnet 36, and the closed armature switch 37. When the circuit of the releasing magnet 36 is thus closed, it withdraws the actuating pawl 17 from the ratchet wheel 11, permitting said ratchet wheel to be moved to a position in which the wipers 12 12¹, 12² are out of engagement with waiting contacts. As soon as the wipers are placed out of contact with waiting contacts, the switch 25 is opened and the circuit of the releasing magnet 36 is consequently broken, whereby said magnet permits the reengagement of the holding and actuating pawls 17 with the ratchet wheel 11. The switch 25, 85 when opened, also breaks the circuit for the locking magnet 21 and also removes the battery 19 from connection with the test thimbles 26 by way of the switch 25, substitute connections with the thimbles 26 being established for testing purposes by the cord circuits, in accordance with common practice. 90

When the subscribers are through conversation, the operator will take down the link connector employed to unite the subscribers' lines, whereupon the apparatus will be completely restored to the normal condition illustrated. 95

It will be apparent from what has been described, that each responsive device which is common to a group of link connectors has a plurality of groups of waiting contacts, similarly related waiting contacts of the different groups being in multiple connection, the different groups of waiting contacts being distributed among the selecting devices, each selecting device thus having one group of waiting contacts belonging to one responsive device, another group of 100 waiting contacts belonging to another responsive device, a third group of waiting contacts belonging to a third responsive device, and so on, the wiping contacts engaging one group of waiting contacts and resting in engagement therewith if the circuit governing the responsive device associated with said waiting contacts has its normal ground connection 27, but passing out of connection with such waiting contacts if 110 such ground 27 is removed, the wipers continuing to move until they have encountered a group of contacts one of which has the ground 27 connected therewith. Thus a calling subscriber or other 120 calling party, by setting his selecting mechanism into operation, will associate himself with an operator who is in position to answer his call. The system of my invention, therefore, is of great importance, in 130

that it enables an operator to work to her proper capacity without being overtaxed. the speed with which the operator performs her duties alone determining the amount of work that she is to perform.

Each operator desirably has an ample number of cord circuits assigned to her which are preferably equal to or slightly in excess of the number that she can handle when she is operating at her fullest efficiency. If she has used all of the cord circuits that have been assigned to her, she will temporarily shift the switch 28 until some of her cord circuits are released and taken down, whereupon she will restore the switch 28 to its closed position. If it is desired to take operators off of duty, the switches 28 of such operators are opened. In this way the business of the exchange may be assigned to the number of operators that are capable of handling it, a lesser number of operators being required during the lighter periods of the day and more operators being required during the heavier periods of the day, all as will be apparent.

It is further obvious that with the system of my invention main and intermediate distributing boards may be dispensed with, line signals in fixed association with the lines may be discarded, as well as the answering jacks of such lines when the invention is employed in connection with multiple switchboards.

In the preferred embodiment of the invention, I do not use manually operated listening keys, but cause the magnets 35 to operate listening keys 35¹, these magnets 35 causing the operator's telephone equipment 32 to be included in circuit when the link connectors are connected with calling lines, so that the operator may converse with the calling subscriber. These results are accomplished in connection with responsive devices, one herein shown as being provided for each operator and common to her group of connectors, but I do not wish to be limited to responsive devices that are thus common to groups of link connectors.

Initially, as has been explained, the operator's telephone equipment is connected with a calling line by means of the selecting mechanism of the calling line, and inasmuch as there may be no line signals in fixed association with the lines, the operator will not have the facilities afforded by such line signals for informing her as to the numbers of the calling lines. She may ascertain the number of the calling line by conversing with the calling subscriber through the telephonic circuit established by the selecting mechanism, or if it is desired to relieve the calling subscriber of the burden of informing the operator of his number, a phonograph 38, one per line, and preferably constantly operating, may be employed to speak

into a transmitter 39 the number of the calling line, each phonograph serving to speak the number of its own associate line. The transmitter 39 is looped into the conductor that unites the waiting contact 12¹ 70 with the alternate contact 33, so that the operator whose telephone equipment is then in circuit with the wiper 12¹ will ascertain the number of the calling subscriber without burdening the calling subscriber with this 75 function.

In the claims I speak of responsive devices for the link connectors by which expression I mean that the responsive devices are associated with the link connectors. I do not limit myself to any circuit association between the link connectors and the responsive devices.

While I have herein shown and particularly described the preferred embodiment of my invention, I do not wish to be limited to the precise details of construction and circuit arrangement shown, but,

Having thus described my invention, I claim as new and desire to secure by Letters Patent the following:—

1. A telephone exchange system including lines extending from telephone stations to an exchange, a plurality of groups of operators' link connectors at the exchange 95 for uniting lines in conversation, an operator's telephone outfit for each group of link connectors and common to the link connectors of such group, selecting mechanism governed by calling lines adapted to select 100 and permit the operation of the operator's telephone outfit free to be operated, means made effective by the link connectors of each group that are taken for use to prevent the responsive device associated with such group 105 from being selected for operation, and mechanism governed by the connecting ends of the link connectors and serving, when taken for use, to release the operators' telephone outfits, again to render them free for 110 selection by the calling lines.

2. A telephone exchange system including lines extending from telephone stations to an exchange, a plurality of groups of operators' link connectors at the exchange for 115 uniting lines in conversation, a responsive device for each group of link connectors and common to the link connectors of such group, selecting mechanism governed by calling lines adapted to select and permit 120 the operation of the responsive device free to be operated, means made effective by the link connectors of each group that are taken for use to prevent the responsive device associated with such group from being selected 125 for operation, operators' telephones for the groups of link connectors, switching means governed by the selecting mechanism and actuated by operated selecting mechanism to bring the operators' telephones as- 130

sociated with the selected responsive devices into telephonic association with the calling lines, and mechanism governed by the connecting ends of the link connectors and serving, when taken for use, to release the responsive devices, again to render them free for selection by the calling lines.

3. A telephone exchange system including lines extending from telephone stations to an exchange, a plurality of groups of operators' link connectors at the exchange for uniting lines in conversation, an operator's telephone outfit for each group of link connectors and common to the link connectors of such group, selecting devices individual to the telephone lines and operated by calling lines to select and permit the operation of the responsive device free to be operated, means made effective by the link connectors of each group that are taken for use to prevent the operator's telephone outfit associated with such group from being selected for operation, and mechanism governed by the connecting ends of the link connectors and serving, when taken for use, to release the operators' telephone outfits, again to render them free for selection by the calling lines.

4. A telephone exchange system including lines extending from telephone stations to an exchange, a plurality of groups of operators' link connectors at the exchange for uniting lines in conversation, a responsive device for each group of link connectors and common to the link connectors of such group, selecting devices individual to the telephone lines and operated by calling lines to select and permit the operation of the responsive device free to be operated, means made effective by the link connectors of each group that are taken for use to prevent the responsive device associated with such group from being selected for operation, operators' telephones for the groups of link connectors, switching means governed by the selecting mechanism and actuated by operated selecting mechanism to bring the operators' telephones associated with the selected responsive devices into telephonic association with the calling lines, and mechanism governed by the connecting ends of the link connectors and serving, when taken for use, to release the responsive devices, again to render them free for selection by the calling lines.

5. A telephone exchange system including lines extending from telephone stations to an exchange, a plurality of groups of operators' link connectors at the exchange for uniting lines in conversation, an operator's telephone outfit for each group of link connectors and common to the link connectors of such group, selecting mechanism governed by calling lines adapted to select and permit the operation of the operator's tele-

phone outfit free to be operated, and means made effective by actuated selecting mechanism to prevent operators' telephone outfits from being again selected while in operated conditions.

6. A telephone exchange system including lines extending from telephone stations to an exchange, a plurality of groups of operators' link connectors at the exchange for uniting lines in conversation, an operator's telephone outfit for each group of link connectors and common to the link connectors of such group, selecting devices individual to the telephone lines and operated by calling lines to select and permit the operation of the operator's telephone outfit free to be operated, and means made effective by actuated selecting devices to prevent operators' telephone outfits from being again selected while in operated conditions.

7. A telephone exchange system including lines extending from telephone stations to an exchange, a plurality of groups of operators' link connectors at the exchange for uniting lines in conversation, a responsive device for each group of link connectors and common to the link connectors of such group, selecting mechanism governed by calling lines adapted to select and permit the operation of the responsive device free to be operated, means made effective by the link connectors of each group that are taken for use to prevent the responsive device associated with such group from being selected for operation, and mechanism governed by the connecting ends of the link connectors and serving, when taken for use, to release the responsive devices, again to render them responsive to the mechanism governed by the calling lines, the selecting mechanism having contacts and said responsive devices having contacts adapted for engagement with the aforesaid contacts, said responsive devices having the circuits controlling the same altered when the contacts of responsive devices free to be selected are engaged by the selector contacts and said means being in the form of switching devices serving to render ineffective the controlling circuits of responsive devices that are not to be free to be selected.

8. A telephone exchange system including lines extending from telephone stations to an exchange, a plurality of groups of operators' link connectors at the exchange for uniting lines in conversation, a responsive device for each group of link connectors and common to the link connectors of such group, selecting mechanism governed by calling lines adapted to select and permit the operation of the responsive device free to be operated, means made effective by the link connectors of each group that are taken for use to prevent the responsive device associated with such group from being selected

- for operation, operators' telephones for the groups of link connectors, switching means governed by the selecting mechanism and actuated by operated selecting mechanism to bring the operators' telephones associated with the selective responsive devices into telephonic association with the calling lines, and mechanism governed by the connecting ends of the link connectors and serving, when taken for use, to release the responsive devices, again to render them responsive to the mechanism governed by the calling lines, the selecting mechanism having contacts and said responsive devices having contacts adapted for engagement with the aforesaid contacts, said responsive devices having the circuits controlling the same altered when the contacts of responsive devices free to be selected are engaged by the selector contacts and said means being in the form of switching devices serving to render ineffective the controlling circuits of responsive devices that are not to be free to be selected.

9. A telephone exchange system including lines extending from telephone stations to an exchange, a plurality of groups of operators' link connectors at the exchange for uniting lines in conversation, a responsive device for each group of link connectors and common to the link connectors of such group, selecting devices individual to the telephone lines and operated by calling lines to select and permit the operation of the responsive device free to be operated, means made effective by the link connectors of each group that are taken for use to prevent the responsive device associated with such group from being selected for operation, and mechanism governed by the connecting ends of the link connectors and serving, when taken for use, to release the responsive devices, again to render them responsive to the mechanism governed by the calling lines, the selecting devices having contacts and said responsive devices having contacts adapted for engagement with the aforesaid contacts, said responsive devices having the circuits controlling the same altered when the contacts of responsive devices free to be selected are engaged by the selector contacts and said means being in the form of switching devices serving to render ineffective the controlling circuits of responsive devices that are not to be free to be selected.

10. A telephone exchange system including lines extending from telephone stations to an exchange, a plurality of groups of operators' link connectors at the exchange for uniting lines in conversation, a responsive device for each group of link connectors and common to the link connectors of such group, selecting devices individual to the telephone lines and operated by calling lines to select and permit the operation of the responsive device free to be operated, means made effective by the link connectors of each group that are taken for use to prevent the responsive device associated with such group from being selected for operation, operators' telephones for the groups of link connectors, switching means governed by the selecting mechanism and actuated by operated selecting mechanism to bring the operators' telephones associated with the selected responsive devices into telephonic association with the calling lines, and mechanism governed by the connecting ends of the link connectors and serving, when taken for use, to release the responsive devices, again to render them responsive to the mechanism governed by the calling lines, the selecting devices having contacts and said responsive devices having contacts adapted for engagement with the aforesaid contacts, said responsive devices having the circuits controlling the same altered when the contacts of responsive devices free to be selected are engaged by the selector contacts and said means being in the form of switching devices serving to render ineffective the controlling circuits of responsive devices that are not to be free to be selected.

11. A telephone exchange system including lines extending from telephone stations to an exchange, a plurality of groups of operators' link connectors at the exchange for uniting lines in conversation, a responsive device for each group of link connectors and common to the link connectors of such group, selecting mechanism governed by calling lines adapted to select and permit the operation of the responsive device free to be operated, and means governed by the operators to prevent responsive devices from being selected for operation, the selecting mechanism having contacts and said responsive devices having contacts adapted for engagement with the aforesaid contacts, said responsive devices having the circuits controlling the same altered when the contacts of responsive devices free to be selected are engaged by the selector contacts and said means being in the form of switching devices serving to render ineffective the controlling circuits of responsive devices that are not to be free to be selected.

12. A telephone exchange system including lines extending from telephone stations to an exchange, a plurality of groups of operators' link connectors at the exchange for uniting lines in conversation, a responsive device for each group of link connectors and common to the link connectors of such group, selecting devices individual to the telephone lines and operated by calling lines to select and permit the operation of the responsive device free to be operated, and means governed by the operators to prevent responsive devices from being selected for operation, the selecting devices having con-

5 contacts and said responsive devices having contacts adapted for engagement with the aforesaid contacts, said responsive devices having the circuits controlling the same altered when the contacts of responsive devices free to be selected are engaged by the selector contacts and said means being in the form of switching devices serving to render ineffective the controlling circuits of responsive devices that are not to be free to be selected.

13. A telephone exchange system including lines extending from telephone stations to an exchange, a plurality of groups of operators' link connectors at the exchange for uniting lines in conversation, a responsive device for each group of link connectors and common to the link connectors of such group, selecting mechanism governed by calling lines adapted to select and permit the operation of the responsive device free to be operated, and means made effective by actuated selecting mechanism to prevent the responsive devices from being again selected while in operated conditions, the selecting mechanism having contacts and said responsive devices having contacts adapted for engagement with the aforesaid contacts, said responsive devices having the circuits controlling the same altered when the contacts of responsive devices free to be selected are engaged by the selector contacts and said means being in the form of switching devices serving to render ineffective the controlling circuits of responsive devices that are not to be free to be selected.

14. A telephone exchange system including lines extending from telephone stations to an exchange, a plurality of groups of operators' link connectors at the exchange for uniting lines in conversation, a responsive device for each group of link connectors and common to the link connectors of such group, selecting devices individual to the telephone lines and operated by calling lines to select and permit the operation of the responsive device free to be operated, and means made effective by actuated selecting devices to prevent responsive devices from being again selected while in operated conditions, the selecting devices having contacts and said responsive devices having contacts adapted for engagement with the aforesaid contacts, said responsive devices having the circuits controlling the same altered when the contacts of responsive devices free to be selected are engaged by the selector contacts and said means being in the form of switching devices serving to render ineffective the controlling circuits of responsive devices that are not to be free to be selected.

15. A telephone exchange system including lines extending from telephone stations to an exchange, a plurality of groups of

operators' link connectors at the exchange for uniting lines in conversation, an operator's telephone outfit for each group of link connectors and common to the link connectors of such group, mechanism governed by calling lines adapted to permit the operation of the operator's telephone outfit free to be operated, means made effective by the link connectors of each group that are taken for use to prevent the operator's telephone outfit associated with such group from being operated, and mechanism governed by the connecting ends of the link connectors and serving, when taken for use, to release the operator's telephone outfit, again to render them responsive to the mechanism governed by the calling lines.

16. A telephone exchange system including lines extending from telephone stations to an exchange, a plurality of groups of operators' link connectors at the exchange for uniting lines in conversation, a responsive device for each group of link connectors and common to the link connectors of such group, mechanism governed by calling lines adapted to permit the operation of the responsive device free to be operated, means made effective by the link connectors of each group that are taken for use to prevent the responsive device associated with such group from being operated, operators' telephones for the groups of link connectors, switching means governed by the mechanism and actuated by operated mechanism to bring the operators' telephones associated with the responsive devices into telephonic association with the calling lines, and mechanism governed by the connecting ends of the link connectors and serving, when taken for use, to release the responsive devices, again to render them responsive to the mechanism governed by the calling lines.

17. A telephone exchange system including lines extending from telephone stations to an exchange, a plurality of groups of operators' link connectors at the exchange for uniting lines in conversation, a responsive device for each group of link connectors and common to the link connectors of such group, mechanism governed by calling lines adapted to permit the operation of the responsive device free to be operated, means made effective by the link connectors of each group that are taken for use to prevent the responsive device associated with such group from being operated, and mechanism governed by the connecting ends of the link connectors and serving, when taken for use, to release the responsive devices, again to render them responsive to the mechanism governed by the calling lines, the first aforesaid mechanism having contacts and said responsive devices having contacts adapted for engagement with the aforesaid contacts, said responsive devices having the circuits

controlling the same altered when the contacts of responsive devices free to be operated are engaged by the contacts and said means being in the form of switching devices serving to render ineffective the controlling circuits of responsive devices that are not to be free to be operated.

18. A telephone exchange system including lines extending from telephone stations to an exchange, a plurality of groups of operators' link connectors at the exchange for uniting lines in conversation, a responsive device for each group of link connectors and common to the link connectors of such group, mechanism governed by calling lines adapted to permit the operation of the responsive device free to be operated, means made effective by the link connectors of each group that are taken for use to prevent the responsive device associated with such group from being operated, operators' telephones for the groups of link connectors, switching means governed by the mechanism and actuated by operated mechanism to bring the operators' telephones associated with the responsive devices into telephonic association with the calling lines, and mechanism governed by the connecting ends of the link connectors and serving, when taken for use, to release the responsive devices, again to render them responsive to the mechanism governed by the calling lines, the first aforesaid mechanism having contacts and said responsive devices having contacts adapted for engagement with the aforesaid contacts, said responsive devices having the circuits controlling the same altered when the contacts of responsive devices free to be operated are engaged by the contacts and said means being in the form of switching devices serving to render ineffective the controlling circuits of responsive devices that are not to be free to be operated.

19. A telephone exchange system including lines extending from telephone stations to an exchange, a plurality of groups of operators' link connectors at the exchange for uniting lines in conversation, a responsive device for each group of link connectors and common to the link connectors of such group, mechanism governed by calling lines adapted to permit the operation of the responsive device free to be operated, and means governed by the operators to prevent responsive devices from being operated, the aforesaid mechanism having contacts and said responsive devices having contacts adapted for engagement with the aforesaid contacts, said responsive devices having the circuits controlling the same altered when the contacts of responsive devices free to be operated are engaged by the contacts and said means being in the form of switching devices serving to render ineffective the con-

trolling circuits of responsive devices that are not to be free to be operated.

20. A telephone exchange system including lines extending from telephone stations to an exchange, a plurality of groups of operators' link connectors at the exchange for uniting lines in conversation, a responsive device for each group of link connectors and common to the link connectors of such group, mechanism governed by calling lines adapted to permit the operation of the responsive device free to be operated, and means made effective by actuated mechanism to prevent responsive devices from being again taken for operation while in operated conditions, the aforesaid mechanism having contacts and said responsive devices having contacts adapted for engagement with the aforesaid contacts, said responsive devices having the circuits controlling the same altered when the contacts of responsive devices free to be operated are engaged by the contacts and said means being in the form of switching devices serving to render ineffective the controlling circuits of responsive devices that are not to be free to be operated.

21. A telephone exchange system including lines extending from telephone stations to an exchange, a plurality of groups of operators' link connectors at the exchange for uniting lines in conversation, a responsive device for each group of link connectors and common to the link connectors of such group, switching mechanism governed by calling lines adapted to permit the operation of the responsive device free to be operated, and means made effective by actuated switching mechanism to prevent responsive devices from being again taken for operation while in operated conditions, the aforesaid mechanism having contacts and said responsive devices having contacts adapted for engagement with the aforesaid contacts, said responsive devices having the circuits controlling the same altered when the contacts of responsive devices free to be operated are engaged by the contacts and said means being in the form of switching devices serving to render ineffective the controlling circuits of responsive devices that are not to be free to be operated.

22. A telephone exchange system including lines extending from telephone stations to an exchange, a plurality of groups of operators' link connectors at the exchange for uniting lines in conversation, a responsive device for each group of link connectors and common to the link connectors of such group, selecting mechanism governed by calling lines adapted to select and permit the operation of the responsive device free to be operated, and means for preventing responsive devices from being selected for operation, the selecting mecha-

nism having contacts and said responsive devices having contacts adapted for engagement with the aforesaid contacts, said responsive devices having the circuits controlling the same altered when the contacts of responsive devices free to be selected are engaged by the selector contacts and said means being in the form of switching devices serving to render ineffective the controlling circuits of responsive devices that are not to be free to be selected.

23. A telephone exchange system including lines extending from telephone stations to an exchange, a plurality of groups of operators' link connectors at the exchange for uniting lines in conversation, a responsive device for each group of link connectors and common to the link connectors of such group, selecting devices individual to the telephone lines and operated by calling lines to select and permit the operation of the responsive device free to be operated, and means for preventing responsive devices from being selected for operation, the selecting devices having contacts and said responsive devices having contacts adapted for engagement with the aforesaid contacts, said responsive devices having the circuits controlling the same altered when the contacts of responsive devices free to be selected are engaged by the selector contacts and said means being in the form of switching devices serving to render ineffective the controlling circuits of responsive devices that are not to be free to be selected.

24. A telephone exchange system including lines extending from telephone stations to an exchange, a plurality of groups of operators' link connectors at the exchange for uniting lines in conversation, a responsive device for each group of link connectors and common to the link connectors of such group, mechanism governed by calling lines adapted to permit the operation of the responsive device free to be operated, and means for preventing responsive devices from being operated, the aforesaid mechanism having contacts and said responsive devices having contacts adapted for engagement with the aforesaid contacts, said responsive devices having the circuits controlling the same altered when the contacts of responsive devices free to be operated are engaged by the contacts and said means being in the form of switching devices serving to render ineffective the controlling circuits of responsive devices that are not to be free to be operated.

25. A telephone exchange system including lines extending from telephone stations to an exchange, a plurality of groups of operators' link connectors at the exchange for uniting lines in conversation, a responsive device for each group of link connectors and common to the link connectors of such

group, selecting mechanism governed by calling lines adapted to select and permit the operation of the responsive device free to be operated, means for preventing responsive devices from being selected for operation, the selecting mechanism having contacts and said responsive devices having contacts adapted for engagement with the aforesaid contacts, said responsive devices having the circuits controlling the same altered when the contacts of responsive devices free to be selected are engaged by the selector contacts and said means being in the form of switching devices serving to render ineffective the controlling circuits of responsive devices that are not to be free to be selected, and means for restoring the operated responsive device to its normal condition.

26. A telephone exchange system including lines extending from telephone stations to an exchange, a plurality of groups of operators' link connectors at the exchange for uniting lines in conversation, a responsive device for each group of link connectors and common to the link connectors of such group, mechanism governed by calling lines adapted to permit the operation of the responsive device free to be operated, means for preventing responsive devices from being operated, the aforesaid mechanism having contacts and said responsive devices having contacts adapted for engagement with the aforesaid contacts, said responsive devices having the circuits controlling the same altered when the contacts of responsive devices free to be operated are engaged by the contacts and said means being in the form of switching devices serving to render ineffective the controlling circuits of responsive devices that are not to be free to be operated, and means for restoring the operated responsive device to its normal condition.

27. A telephone exchange system including lines extending from telephone stations to an exchange, a plurality of groups of operators' link connectors at the exchange, responsive devices for said groups of link connectors, and selecting mechanism governed by calling lines adapted to select responsive devices free for selection, said link connectors having operator controlled means to adapt them to their telephone line joining function independently of the aforesaid selecting mechanism.

28. A telephone exchange system including lines extending from telephone stations to an exchange, a plurality of groups of operators' link connectors at the exchange, responsive devices for said groups of link connectors one common to connectors of each group, and selecting mechanism governed by calling lines adapted to select responsive devices free for selection, said link connectors having operator controlled means to

adapt them to their telephone line joining function independently of the aforesaid selecting mechanism.

29. A telephone exchange system including lines extending from telephone stations to an exchange, a plurality of groups of operators' link connectors at the exchange, conductors associated with each group of connectors for connecting operators' telephones

10 with calling lines, and selecting mechanism governed by calling lines adapted to select connectors free for selection, said link conductors having operator controlled means to adapt them to their telephone line joining function independently of the aforesaid selecting mechanism.

30. A telephone exchange system including lines extending from telephone stations to an exchange, a plurality of groups of operators' link connectors at the exchange, responsive devices for said groups of link connectors, selecting mechanism governed by calling lines adapted to select responsive devices free for selection, said link connectors having operator controlled means to adapt them to their telephone line joining function independently of the aforesaid selecting mechanism, and operator controlled means for freeing said responsive devices so that they

30 may be subject to further selection.

31. A telephone exchange system including lines extending from telephone stations to an exchange, a plurality of groups of operators' link connectors at the exchange, responsive devices for said groups of link connectors one common to connectors of each group, selecting mechanism governed by calling lines adapted to select responsive devices free for selection, said link connectors having operator controlled means to adapt them to their telephone line joining function independently of the aforesaid selecting mechanism, and operator controlled means for freeing said responsive devices so that they

45 may be subject to further selection.

32. A telephone exchange system including lines extending from telephone stations to an exchange, a plurality of groups of operators' link connectors at the exchange, conductors associated with each group of connectors for connecting operators' telephones with calling lines, selecting mechanism governed by calling lines adapted to select conductors free for selection, said link connectors having means to adapt them to their telephone line joining function independently of the aforesaid selecting mechanism, and operator controlled means for restoring said conductors to selectable condition.

33. A telephone exchange system including lines extending from telephone stations to an exchange, a plurality of groups of operators' link connectors at the exchange, responsive devices for said groups of link con-

nectors, selecting mechanism governed by calling lines adapted to select responsive devices free for selection, and automatic means for guarding responsive devices when in selected conditions from further selection, said link connectors having operator controlled means to adapt them to their telephone line joining function independently of the aforesaid selecting mechanism. 70

34. A telephone exchange system including lines extending from telephone stations to an exchange, a plurality of groups of operators' link connectors at the exchange, responsive devices for said groups of link connectors, one common to connectors of each group, selecting mechanism governed by calling lines adapted to select responsive devices free for selection, and automatic means for guarding responsive devices when in selected conditions from further selection, said link connectors having means to adapt them to their telephone line joining function independently of the aforesaid selecting mechanism. 75 80

35. A telephone exchange system including lines extending from telephone stations to an exchange, a plurality of groups of operators' link connectors at the exchange, responsive devices for said groups of link connectors, selecting mechanism governed by calling lines adapted to select responsive devices free for selection, automatic means for guarding responsive devices when in selected conditions from further selection, said link connectors having operator controlled means to adapt them to their telephone line joining function independently of the aforesaid selecting mechanism, and operator controlled means for freeing said responsive devices so that they may be subject to further selection. 90 95

36. A telephone exchange system including lines extending from telephone stations to an exchange, a plurality of groups of operators' link connectors at the exchange, responsive devices for said groups of link connectors, one common to connectors of each group, selecting mechanism governed by calling lines adapted to select responsive devices free for selection, automatic means for guarding responsive devices when in selected conditions from further selection, said link connectors having means to adapt them to their telephone line joining function independently of the aforesaid selecting mechanism, and operator controlled means for freeing said responsive devices so that they may be subject to further selection. 100 105 110 115

37. A telephone exchange system including lines extending from telephone stations to an exchange, a plurality of groups of operators' link connectors at the exchange, conductors associated with each group for connecting operators' telephones with calling lines, selecting mechanism governed by 120 125 130

calling lines adapted to select conductors free for selection, and automatic means for guarding such conductors when in selected conditions from further selection, said link connectors having operator controlled means to adapt them to their telephone line joining function independently of the aforesaid selecting mechanism.

38. A telephone exchange system including lines extending from telephone stations to an exchange, a plurality of groups of operators' link connectors at the exchange, conductors associated with each group for connecting operators' telephones with calling lines, one common to connectors of each group, selecting mechanism governed by calling lines adapted to select conductors free for selection, automatic means for guarding such conductors when in selected conditions from further selection, said link connectors having means to adapt them to their telephone line joining function independently of the aforesaid selecting mechanism, and operator controlled means for restoring said conductors to selectable condition.

39. A telephone exchange system including lines extending from telephone stations to an exchange, a plurality of link connectors at the exchange adapted to the use of operators in making connections between lines, operators' responsive devices, and selecting mechanism adapted to select responsive devices free for selection, said link connectors having operator controlled means to adapt them to their line joining function independently of the aforesaid selecting mechanism.

40. A telephone exchange system including lines extending from telephone stations to an exchange, a plurality of link connectors at the exchange adapted to the use of operators in making connections between lines, operators' telephones, and selecting mechanism for selecting operators' telephones free for selection and associating them with calling lines, said link connectors having operator controlled means to adapt them to their line joining function independently of the aforesaid selecting mechanism.

41. A telephone exchange system including lines extending from telephone stations to an exchange, a plurality of groups of operators' link connectors at the exchange for uniting lines in conversation, a responsive device for each group of link connectors and common to the link connectors of such group, selecting devices individual to the telephone lines and operated by calling lines to select and permit the operation of the responsive device free to be operated, means for preventing responsive devices from being selected for operation, the selecting devices having contacts and said responsive devices having

contacts adapted for engagement with the aforesaid contacts, said responsive devices having the circuits controlling the same altered when the contacts of responsive devices free to be selected are engaged by the selector contacts and said means being in the form of switching devices serving to render ineffective the controlling circuits of responsive devices that are not to be free to be selected, and means for restoring the operated responsive device to its normal condition. 75

42. A telephone exchange system including lines extending from telephone stations to an exchange, a plurality of link connectors at the exchange adapted to the use of operators in making connections between lines, operators' responsive devices, and automatically operating electro-magnetic switching mechanism for associating free responsive devices with calling lines, said link connectors having operator controlled means to adapt them to their line joining functions independently of said switching mechanism. 80

43. A telephone system including lines extending from telephone stations to an exchange, responsive devices governing the connection of operators' telephones with telephone lines at the exchange, and means for selecting an idle responsive device. 90

44. A signaling system including a plurality of signaling lines, signal receivers, selector switches for selecting signal receivers that are free for selection and associating the same with signaling lines, and means individual to the lines and which differ from each other for causing said signal receivers to give characteristic signals peculiar to the lines. 95

45. A signaling system including a plurality of signaling lines, telephone receivers, selector switches for selecting telephone receivers that are free for selection and associating the same with calling lines, and phonographs individual to the lines and each capable of speaking the designation of the line to which it is individual, said phonographs serving to operate the telephone receivers to announce the designations of the lines. 105

46. A telephone system including a plurality of telephone lines extending to an exchange, signal receivers at different operators' positions, selector switches operated by calling telephone lines for selecting signal receivers that are free for selection and associating the same with calling telephone lines, and means individual to the lines and which differ from each other for causing said signal receivers to give characteristic signals peculiar to the lines. 115

47. A telephone system including a plurality of telephone lines extending to an exchange, telephone receivers at different operators' positions, selector switches operated by calling telephone lines for selecting tele- 120 125 130 135 140 145 150 155 160 165 170 175 180

- phone receivers that are free for selection and associating the same with calling lines, and phonographs individual to the lines and each capable of speaking the designation of the line to which it is individual, said phonographs serving to operate the telephone receivers to announce the designations of the lines.
48. A telephone system including a plurality of telephone lines extending to an exchange, signal receivers at different operators' positions, selector switches for selecting signal receivers that are free for selection and associating the same with calling telephone lines, and means individual to the lines and which differ from each other for causing said signal receivers to give characteristic signals peculiar to the lines.
49. A telephone system including a plurality of telephone lines extending to an exchange, telephone receivers at different operators' positions, selector switches for selecting telephone receivers that are free for selection and associating the same with calling lines, and phonographs individual to the lines and each capable of speaking the designation of the line to which it is individual, said phonographs serving to operate the telephone receivers to announce the designations of the lines.
50. A telephone system having lines, a plurality of link connectors for making connections between lines, operators' telephone outfits, mechanism for selecting an idle operator's telephone outfit, and means to adapt the link connectors to their line joining function independently of the aforesaid mechanism.
51. A telephone exchange system including lines extending from telephone stations to an exchange, a plurality of link connectors at the exchange adapted to the use of operators in making connections between lines, operators' telephones, and automatics.
52. A telephone system having lines, a plurality of link connectors for making connections between lines, responsive devices, mechanism for selecting an idle responsive device, and means to adapt the link connectors to their line joining function independently of the aforesaid mechanism.
53. A telephone exchange system including lines extending from telephone stations to an exchange, link connectors at the exchange for uniting lines in conversation, operators' telephone outfits associated with different operators' positions, selecting mechanism governed by calling lines for selecting idle operators' telephone outfits, and means operating independently of link connectors for preventing selection of operators' telephone outfits that are in selected condition.
54. A telephone exchange system including lines extending from telephone stations to an exchange, link connectors at the exchange for uniting lines in conversation, operators' responsive devices associated with different operators' positions, selecting mechanism governed by calling lines for selecting idle operators' responsive devices, and means operating independently of link connectors for preventing selection of operators' responsive devices that are in selected condition.

In witness whereof, I hereunto subscribe my name this 14th day of June, A. D., 1909.

ELMER R. CORWIN.
